UNITED STATES PATENT OFFICE.

MANLEY A. BOWEN, OF FRESNO, CALIFORNIA.

SUPPORT FOR TELEPHONE RECEIVERS.

Application filed July 13, 1921. Serial No. 424,402.

To all whom it may concern:

Be it known that I, MANLEY A. BOWEN, a citizen of the United States, and resident of Fresno, in the county of Fresno 5 and the State of California, have invented a new and useful Improvement in Supports for Telephone Receivers, of which the following is a specification.

My invention relates to a receiver support 10 for desk telephones. The object is to hold the receiver of the telephone stationary and adjacent to the ear of the speaker so that both hands may be free for making notations or for other uses. While the arm is 15 thus extended, the receiver hook is released and the electrical circuit is completed. When the receiver support is pushed to an approximately vertical position, the receiver hook is depressed and the circuit opened.

I accomplish these objects by means 20 of the mechanism illustrated in the accompanying drawing in which Figure 1 is a side view of a desk telephone with the telephone attachment in position for talking. Figure 2 is a fractional view 25 of the telephone and the attachment showing the receiver supporting arm in position with the receiver hook depressed. Figure 3 is a fractional reverse view of the 30 clamp extension and receiver support showing the stop which limits the movement of the receiver support. In the drawing A is a clamp attached to the upright post of a telephone. A¹ is an extending support of 35 clamp A, supporting arm B which swings at pivot P and to which the receiver K may be clamped by clamp B². B¹ is an extension of arm B opposite the end to which the receiver is attached, which depresses 40 receiver hook E when arm B is pushed slightly past a vertical position, as shown in Figure 2. Support A¹ has a stop D thereon, to limit the movement of arm B. C is 45 a depending rod pivoted to arm B. Its function is to support receiver arm B when arm B is dropped, by resting upon the surface of the desk or other object upon which the telephone stands. Depending rod C has

a weight C¹ at the lower end thereof, the object being to counterbalance the weight 50 of the receiver when the telephone is made inoperative. When it is desired to use the telephone, depending rod C is pulled away from the telephone and the weight C¹ is 55 rested upon the surface of the object upon which the telephone stands. This movement raises arm extension B¹ from contact with receiver hook E which is thereby released, closing the electrical circuit necessary to make the telephone operative, receiver K is lowered into position adjacent 60 to the ear of the speaker and is held in that position by depending rod C.

When the telephone is not in use, depending rod C is pushed to an approximately 65 vertical position where it normally rests. This movement returns receiver K to a position of rest above the mouthpiece of the telephone and arm extension B¹ depresses receiver hook E thereby opening the electrical circuit.

I claim as new and ask for Letters Patent.

In combination with a desk telephone having an upright support, a transmitter, a receiver, and a hook adapted to hold the receiver and to disconnect the electrical circuit when the receiver is depressed, of a member adapted to be clamped to the support, an arm pivoted to the clamped member, said arm having at one end an extension adapted to depress the telephone hook when the arm is raised approximately vertically and to release the hook when the arm is moved to extend outwardly from the support, means on said arm for holding the receiver, and a rigid support weighted at one end and pivoted to the arm at the other end, and adapted to automatically swing to a vertical position as the arm is moved, stop means on said clamp, and means on said 75 arm adapted to cooperate with said stop means when the arm is raised vertically to a position at which the weighted support 80 counterbalances the telephone receiver.

MANLEY A. BOWEN.
